change and the pressure will remain about the operating pressure until the engine has stopped to receive the exhaust gases. The opposite side of the annular combustion engine and a postive side of the annular combustion engine and a connection from said engine entering said chamber and the force of each exhaust charge is practically the same. In this operation the opposite side of each plane generally at a right angle to the plane of the propeller. The propeller is made of such a shape that it will not interfere with the propeller. The propeller is made of such a shape that it will not interfere with the propeller.

charge and its gases will rush about the opposite side of the annular portion and in the opposite direction. In this operation the force of each exhaust charge is practically expended before the gases have made a complete circuit of the annular portion of the exhaust nozzle. Since the annular portion of the nozzle is open about its upper side, the moment the gases strike it some of them escape upward, and it is this upward escape of the exhaust gases which to a considerable extent serves to diminish their velocity. The velocity of the exhaust gases is thus largely diminished and the noise of the exhaust is muffled.

The arrangement shown, however, has an additional purpose. Since the exhaust gases are discharged upward from out the annular portion of the nozzle and since the radiator casing is open both at its top and its bottom the exhaust gases set up a current of air, drawing air in at the bottom of the casing and discharging it at the top by an injector action. During the time of the operation of the engine there is, therefore, a continual current of air passing through the radiator casing. The air which is about the radiator, of course, normally becomes heated and this air of itself will rise and will pass out of the radiator casing and will therefore set up something of a current of air, but the arrangement of the exhaust nozzle and the exhaust gases greatly increases the flow of air, and thus very greatly multiplies the quantity of air which will pass through the radiator in a given time and so serves to improve its cooling qualities.

The hood over the top of the radiator casing serves to constrict to some extent the passage through which the air must pass. It is to be noted that the upper edge of the passage where it joins the lower edge of the funnel is larger in diameter than the annular opening in the top of the exhaust nozzle and that it is situated above the exhaust nozzle and that the upper edge of the funnel is flared outwardly from its lower edge. This combination greatly improves the action of the assembly and increases the amount of air which is drawn through the radiator and the radiator casing. This effect is in some measure due to the modified venturi which is formed by the arrangement of the parts just described.

55 I claim:

1. In combination with a radiator a casing enclosing the same, said casing open at its top and bottom and means for positively drawing air in at the bottom of said casing and through said radiator and for forcing the same out at the top of the casing, said means comprising a combined muffler and ejector, said muffler of generally annular plan and provided with a single annular outlet port extending about said muffler, said

means adapted to receive the exhaust gases from an internal combustion engine and a connection from said engine entering said muffler in a plane generally at a right angle to the plane of such annular outlet port.

2. In combination with an internal combustion engine a radiator and a casing enclosing the same, said casing open at its top and bottom and being narrowed at its top and being upwardly and outwardly flared above such narrowed portion to form a modified venturi, means for drawing air in at the bottom of said casing and through said radiator and for forcing the same out through the funnel, said means comprising a combined muffler and ejector adapted to receive the exhaust gases from an internal combustion engine, said combined muffler and ejector being of generally annular plan and tubular section and provided with a single annular opening about the interior of the annulus and a connection from said engine entering said muffler in a plane generally at a right angle to the plane of such annular outlet port.

3. In combination with an internal combustion engine a radiator and a casing enclosing the same, said casing open at its top and bottom and being narrowed at its top and being upwardly and outwardly flared above such narrowed portion to form a modified venturi, means for drawing air in at the bottom of said casing and through said radiator and for forcing the same out through the funnel, said means comprising a combined muffler and ejector adapted to receive the exhaust gases from an internal combustion engine, said combined muffler and ejector being of generally annular plan and tubular section, and provided with a single annular opening about the interior of the annulus, said annulus and annular opening shaped and adapted to cause the exhaust gases from the said internal combustion engine which are discharged into the annulus to rush about it and to escape through the annular opening, thus to set up an ejector action which establishes a current of air through the casing and through the radiator.

4. In combination with a radiator a casing enclosing the same, said casing open at its top and bottom, and means for positively drawing air in at the bottom of said casing and through said radiator, and for forcing the same out at the top of the casing, said means comprising a combined muffler and ejector, said muffler provided with a single annular outlet port extending about said muffler, said muffler adapted to receive the exhaust from an internal combustion engine and provided with a plurality of oppositely directed separate exhaust connections from said engine.

5. In combination with a radiator a casing
